UNITED STATES PATENT OFFICE.

STEPHEN ANDRZEJEWSKI, OF GRAND RAPIDS, MICHIGAN, ASSIGNOR OF ONE-HALF
TO EGBERT DE HAAN, OF GRAND RAPIDS, MICHIGAN.

FINISHING OR POLISHING MECHANISM.

Application filed March 29, 1923. Serial No. 628,680.

To all whom it may concern:

Be it known that I, STEPHEN ANDRZEJEWSKI, a Polish native of Russia, who has applied for citizenship of the United States, 5 residing at Grand Rapids, in the county of Kent and State of Michigan, have invented new and useful Improvements in Finishing or Polishing Mechanism, of which the following is a specification.

10 The present invention relates to surface-finishing for work turning in a lathe; and its object is, generally, to provide mechanism of that character improved as herein-after appears; and, more particularly, to 15 provide in such mechanism means for supporting its finishing, polishing or abrading element and for moving the same into and out of contact with the work and also in a direction transverse to said movement; 20 and further, to provide in such mechanism separate finishing elements supported resiliently in contact with the work; and further, to provide separate resilient supporting members for said elements respectively; 25 and further, to provide such elements and members which may be severally applied to and removed from the mechanism.

This and any other objects hereinafter appearing are attained by, and the invention 30 finds preferable embodiment in, the structure hereinafter particularly described in the body of this specification and illustrated by the accompanying drawings, in which:—

Figure 1 is a front view of a lathe to 35 which my surface-finisher is applied, partly vertically sectioned on line 1—1 of Figure 3;

Figure 2 is a transverse sectional view of parts thereof taken on a vertical plane corresponding to line 2—2 of Figure 1;

Figure 3 is a left hand end view of the same;

Figure 4 is a top plan view of a middle portion of my surface-finisher and of a portion of the work being finished thereby;

Figure 5 is a transverse sectional view (much enlarged) of a portion of my surface-finisher taken on a vertical plane corresponding to line 5—5 of Figure 2; and

50 Figure 6 is a front view of a middle portion of my surface-finisher, partly sectioned vertically on line 6—6 of Figure 4.

In the embodiment of the invention chosen for illustration by the drawings and

for detailed description in the body of this 55 specification, my surface-finisher is shown applied, preferably detachably as by screws 1, to the bed 2 of a lathe having the live head stock 3 and dead head stock 4 on which rotates the turned work 5. A pair of arms 60 6, 6 are mounted at 7, in connection with the lathe's bed, on the base 8 of the surface-finisher, swingably toward and away from the rotary axis of the work 5. A lever, 65 designated generally 9 and comprising a strip 10, extensions 11 and an operating handle 12 is fulcrumed at 13 on the arms 6 swingably transversely to the arms' swingable movement.

A surface-finishing element 14, or a series 70 of such elements, are removably clamped by the clamp members 15, 16 carried by the lever 9, such elements being preferably flexible sheets of sand paper as shown. Said series of surface-finishing elements extends 75 in the axial direction of the work. A corresponding series, extending in the same direction, of resilient members 17 are removably clamped by the clamp members 18, 19 carried by the lever, and underlie and yieldingly support the surface-finishing elements 80 14 respectively, such members preferably consisting of resilient fibers, such as broom-straw extending in a direction transverse to the rotary axis of the work, as shown. 85

It will be seen that by reason of the combined swinging movements of the arms 6 and of the lever 9 and parts carried thereby, the surface-finishing elements 14 may be moved by the handle 12 upwardly into contact with the work and also in a direction transverse to said contacting movement; so that practically the entire polishing or finishing upper surfaces of said elements may from time to time be used in surface-finishing or polishing the turning work, thus wearing said polishing surfaces of said elements as uniformly as may be desired and in the most economical manner. The 90 advantage in providing a series of separately movable surface-finishing elements 14 is particularly illustrated in Figure 4, wherein a work piece 5 having ridges and gutters is shown. These elements 14 are, by reason of their separate action, adapted 100 to be yieldingly pressed against such ridges and gutters. 105

It will be seen that the surface-finishing

elements 14 and resilient members 17 may be separately removed when worn and replaced by others.

The clamp members 15, 16 are operated by thumb screws 20, and the clamp members 18, 10 by screws 21.

The invention being intended to be pointed out in the claims, is not to be limited to or by details of construction of the particular embodiment thereof illustrated by the drawings or hereinbefore shown or described.

I claim:

1. In combination with a lathe, a surface-finisher for work in the lathe, comprising: an arm mounted in connection with the lathe's bed swingably toward and away from the rotary axis of the work; a lever fulcrumed on the arm swingably transversely to the arm's swingable movement; a surface-finishing element carried by the lever and adapted to be moved by the swinging of the arm and lever into and out of contact with the work turning in the lathe and also in a direction transverse to its movement into and out of such contact.

2. In combination with a lathe, a surface-finisher for work in the lathe, comprising: a lever longitudinally movable and mounted in connection with the lathe's bed swingably toward and away from the rotary axis of the work; a resilient member carried by the lever; a series, extending in the axial direction of the work, of surface-finishing elements carried by the lever between the work and said member and yieldingly supported by said member.

3. In combination with a lathe, a surface-finisher for work in the lathe, comprising:

a lever longitudinally movable and mounted in connection with the lathe's bed swingably toward and away from the rotary axis of the work; a series, extending in the axial direction of the work, of resilient members carried by the lever; a series, extending in said direction, of surface-finishing elements carried by the lever between the work and said members and yieldingly supported by said members respectively.

4. In combination with a lathe, a surface-finisher for work in the lathe, comprising: a lever longitudinally movable and mounted in connection with the lathe's bed swingably toward and away from the rotary axis of the work; a resilient member carried by the lever and comprising resilient fibers extending in a direction transverse to said axis; a series, extending in the axial direction of the work, of surface-finishing elements carried by the lever between the work and said member and yieldingly supported by said member.

5. In combination with a lathe, a surface-finisher for work in the lathe, comprising: an arm mounted in connection with the lathe's bed swingably toward and away from the rotary axis of the work; a lever fulcrumed on the arm swingably transversely to the arm's swingable movement; a resilient member carried by the lever; a series, extending in the axial direction of the work, of surface-finishing elements carried by the lever between the work and said member and yieldingly supported by said member.

In testimony whereof I have hereunto set my hand at Grand Rapids, Michigan, this 24th day of March 1923.

STEPHEN ANDRZEJEWSKI.
